UNITED STATES PATENT OFFICE

WALLACE B. ROSS, OF SYRACUSE, NEW YORK, ASSIGNOR TO DIEMOLDING CORPORATION, OF CANASTOTA, NEW YORK, A CORPORATION OF NEW YORK

VALVE OPERATING HANDLE

Application filed February 6, 1931. Serial No. 513,865.

This invention relates to a valve-operating handle adapted to be detachably mounted upon the outer end of a valve stem for opening and closing the valve and refers more particularly to handles which are molded from bakelite or other suitable material, by dies under pressure somewhat in the manner of die-casting.

It is frequently desirable to provide the hubs of these handles with extension skirts which, together with the main body of the handle, is adapted to enclose the portions of the valve stem extending beyond the valve case together with the means for securing the handle to the stem.

It would, of course, be desirable to mold the handle and its skirt in one piece, but under the present methods of molding bakelite and analogous materials it has been found to be impractical to mold the skirt integral with the handle, and the main object of the present invention is to mold these parts separately in such manner that they may be easily and quickly assembled one upon the other and upon the valve stem without adding materially to the cost of manufacture.

Another object is to provide the sections with telescoping parts splined one upon the other to turn in unison and for relative axial displacement.

A further object is to provide the skirt section with a suitable shoulder adapted to cooperate with a similar stop on the valve case for limiting the turning movement of the valve and handle connected thereto.

Other objects and uses relating to specific parts of the device will be brought out in the following description.

In the drawings:

Figure 1 is a side elevation of a valve equipped with my improved handle.

Figure 2 is an enlarged vertical sectional view, taken in the plane of line 2-2, Figure 1, showing a portion of the valve case in elevation.

Figure 3 is an enlarged inverted transverse sectional view taken in the plane of line 3-3, Figure 1.

Figure 4 is a transverse sectional view taken in the plane of line 4-4, Figure 1.

Figures 5 and 6 are perspective views respectively of the main body and skirt of the handle.

In order that the invention may be clearly understood I have shown a valve case —1— containing a suitable valve —2— projecting outwardly through the usual gland —3— of the valve case for receiving and supporting a handle —4—.

This handle comprises an outer end section or main body —4— and an inner end section or skirt —5—, the outer end section being provided with a hub —6— projecting inwardly beyond the inner face of its outer portion, said hub being provided with a central lengthwise opening —7— for receiving a portion of the valve stem —2— and suitable fastening means such as a screw —8—.

The intermediate portion of the opening —7— adjacent the outer end of the handle section —4— is reduced in diameter to form a shoulder —9— against which the outer end of the stem —2— is adapted to abut, said stem being provided in its outer end with a threaded socket for receiving the threaded inner end of the screw —8— having its outer end enlarged for engaging the shoulder —9— and thereby firmly clamping the section —4— to the valve stem, but permitting said section to be easily removed by simply removing the screw —8—.

The portion of the socket —7— and adjacent portion of the valve stem —2— extending thereinto are of angular cross section or otherwise formed to spline one part upon the other to cause the handle and valve stem to rotate in unison when hand power is applied to the handle.

The inner end of the hub —6— of the handle section —4— is reduced in diameter to form an annular shoulder —10— against which the outer end of the skirt section —5— is adapted to abut when assembled thereon.

The outer end of the skirt section —5— is provided with a central opening —11— of substantially the same diameter as that of the reduced inner end of the hub —6— to permit telescopic assembly of the skirt section upon said hub.

The periphery of the reduced inner end of

the hub —6— and opening in the outer end of the skirt —5— are mainly cylindrical except that the outer end of the skirt section is provided with an inwardly projecting rib 5 —12— adapted to engage in a corresponding lengthwise groove —13— in the periphery of the reduced portion of the hub, as shown more clearly in Figures 5 and 6, thereby constituting a splined connection between the 10 outer and inner sections —4— and —5— to cause them to turn in unison and also to allow them to be displaced axially one from the other to be withdrawn from the valve stem.

15 The inner end of the skirt section —5— is provided with a central cylindrical socket —14— of somewhat greater diameter than that of the opening —11— to form an annular shoulder —15— which is substantially 20 co-incident with the inner end of the hub section —6— when the outer end of the section —5— is engaged with the shoulder —10—.

25 This socket —14— is adapted to receive and enclose a coil spring —16— and a pair of washers —17— and —18— which are interposed between the outer end of the spring —16— and ledge —15— of the part —5— so that the outer washer may be 30 spring-pressed against the inner end of the hub —6— and also against the shoulder —15— of the skirt —5— to cooperate with the shoulder —10— for holding the sections —4— and —5— against relative axial displacement when assembled for use.

40 The portion of the valve stem —2— immediately adjacent the inner end of the hub —6— is provided with an annular groove —19—, while the outer washer —17— registering with said groove is provided with a radially elongated opening —20—, the outer 45 end of which is enlarged sufficiently to permit it to be removed axially from the angular portion of the valve stem when registered therewith, the inner end of the radial opening —20— being of substantially the same diameter as the groove —19— so that when 50 moved to its operative position, as shown in Figures 2 and 4, it will engage the walls of the groove and thereby hold the spring —16— under compression.

55 The central opening in the inner washer —18— is of slightly greater diameter than that of the adjacent portion of the valve stem so that when the outer washer —17— is removed from the valve stem the inner washer and also the spring —16— may also be removed endwise by outward displacement.

60 The inner end section —5— of the handle is provided with an outwardly projecting peripheral projection —21— forming a stop shoulder which is adapted to cooperate with another stop shoulder —22— on the outer 65 end of the gland —3— for limiting the turn-

ing movement of the handle and valve actuated thereby in opposite directions, and thereby to indicate the "open" and "closed" positions of the valve, as shown more clearly in Figure 4.

70

That is, when the handle is turned in a clockwise direction the stop shoulder or pointer —21— will approach closely to the stop —22— in registration with the indicia "Shut."

75

On the other hand, when the handle is turned in a counterclockwise direction the stop shoulder or pointer —21— may be brought into engagement with the stop shoulder —22— or in registration with the indicia "Open" to indicate that the valve is open.

80

85 While I have shown and described the manner of assembling the handle sections one upon the other and upon the valve stem, it will be remembered that the main feature of the invention consists in molding the outer and inner handle sections separately so that they may be telescopically assembled one 90 within the other and splined one upon the other to cause them to rotate in unison, and that when secured upon the valve stem by means of the screw —8—, both sections will turn together with the valve stem.

95

It is evident, however, that certain changes may be made in the construction of the two sections of the handle without departing from the spirit or object of the invention.

What I claim is:

1. A handle for valve stems comprising an 100 outer end section having its inner end reduced to form a shoulder, and an inner end section telescoping with said reduced end and abutting against said shoulder, the telescoping portions of said sections being splined one upon the other to turn together.

105

2. A handle for valve stems comprising an outer end section having its inner end reduced to form a shoulder, and an inner end section telescoping with said reduced end and abutting against said shoulder, the telescoping portions of said sections being splined one upon the other to turn together, the inner end section having a stop shoulder adapted to co-operate with a companion stop on 110 the valve case for limiting the turning movement of the handle about its axis.

115

3. A handle for valve stems comprising outer and inner co-axial sections having telescoping parts splined one upon the other, the inner section having a socket in its inner end of greater diameter than that of the adjacent end of the outer section to receive a portion 120 of the valve-operating mechanism.

125

4. A handle for valve stems comprising outer and inner co-axial sections having telescoping parts splined one upon the other, the inner section having a socket in its inner end of greater diameter than that of the adjacent end of the outer section to receive a por- 130

tion of the valve-operating mechanism, said outer section having a central lengthwise opening for receiving a portion of a valve stem.

5. The combination with a valve stem, of a handle composed of outer and inner coaxial sections having telescoping parts splined one upon the other, the inner section having a socket in its inner end of greater diameter than the adjacent end of the outer section to form an annular shoulder, means for locking the outer section to the valve stem against relative endwise or turning movement, and means within the socket engaging said shoulder for holding the inner section against inward endwise displacement from the outer section.

In witness whereof I have hereunto set my hand this 29th day of January 1931.

WALLACE B. ROSS.
